Specification for Design.

Patented Apr. 13, 1920.

Application filed July 25, 1919. Serial No. 313,389. Term of patent 7 years.

To all whom it may concern:

Be it known that I, CHARLES H. DAYTON, a citizen of the United States, residing at Iowa City, in the county of Johnson and State of Iowa, have invented a new, original, and ornamental Design for Bottles or Jugs, of which the following is a specification, reference being had to the accompanying drawing, forming part thereof.

In the drawing,
Figure 1 is a front elevation of a bottle or jug showing my new design.

Fig. 2 is a top plan view of the same.
Fig. 3 is a bottom plan view of the same.
What I claim is:

The ornamental design for a bottle or jug, substantially as shown.

CHARLES H. DAYTON.
